CLAIM

The ornamental design for a combined display support and display with three dimensional graphical user interface, as shown and described.

DESCRIPTION

FIG. 1 is a front, top, right perspective view of a first embodiment of a combined display support and display with three dimensional graphical user interface showing our new design;

FIG. 2 is a front, top, left perspective view thereof;

FIG. 3 is another front, top, left perspective view thereof;

FIG. 4 is a front, top perspective view thereof;

FIG. 5 is a front elevational view thereof;

FIG. 6 is a top plan view thereof;

FIG. 7 is front, top, right perspective view of a second embodiment of a combined display support and display with three dimensional graphical user interface showing our new design;

FIG. 8 is a front, top, left perspective view thereof;

FIG. 9 is another front, top, left perspective view thereof;

FIG. 10 is a front, top perspective view thereof;

FIG. 11 is a front elevational view thereof; and,

FIG. 12 is a top plan view thereof.

The broken lines showing portions of the combined display support and display with three dimensional graphical user interface form no part of the claimed design. The dot-dash broken lines defining boundaries of the claimed design form no part of the claimed design.
